UNITED STATES PATENT OFFICE.

BERNHARD WILMSEN, OF PHILADELPHIA, PENNSYLVANIA.

DESIGN FOR A DOLL.

SPECIFICATION forming part of Design No. 24,381, dated June 11, 1895.

Application filed April 29, 1895. Serial No. 547,571. Term of patent 3 $\frac{1}{2}$ years.

To all whom it may concern:

Be it known that I, BERNHARD WILMSEN, a citizen of the United States, residing in the city and county of Philadelphia, State of Pennsylvania, have invented and produced a new and original Design for a Doll, of which the following is a specification, reference being had to the accompanying drawing, forming part thereof.

10 The leading features of my design for a doll are, first, the garments of the same with representations of fluffy linings at their edges; next, spangles on said garments, and, next, the oblique exposed facing on the lower portion 15 of the garment.

In the drawing, A designates the head of the doll, and B represents a hood thereon.

C designates the cape of a cloak, and D designates the body thereof.

E designates spangles on the garments, and 20 F designates an oblique facing on the lower portion of the body of the cloak.

Between the inner and outer layers of the garments are fluffy linings G, which appear 25 at the edges thereof.

H designates a muff on the front of the cloak, and J designates a prop at the feet of the doll.

What I claim is—

The design for a doll substantially as de- 30 scribed and shown.

BERNHARD WILMSEN.
